TRAY FOR MEDICAL EQUIPMENT

Bern D. Folkman, Van Nuys, Calif., assignor to American Hospital Supply Corporation, Evanston, Ill., a corporation of Illinois

Filed July 11, 1968, Ser. No. 12,693

Term of patent 14 years

Int. Cl. D24—99

U.S. Cl. D83—1

I claim:

The ornamental design for a tray for medical equipment, as shown.
